(57) **CLAIM**

The ornamental design for a grill brush, as shown and described.

DESCRIPTION

FIG. 1 is a perspective view of a grill brush of the present invention;

FIG. 2 is a top view thereof;

FIG. 3 is a right side view thereof, the left side being a mirror image; and,

FIG. 4 is a bottom view thereof.

The broken lines shown on the head and the handle in FIGS. 1 and 3 illustrate portions of the grill brush that form no part of the claimed design. The shaft portion is shown broken away in FIGS. 2-4 for ease of illustration.
